[57] **CLAIM**

The ornamental design for a portable dock fender, as shown and described.

DESCRIPTION

FIG. 1 is a front elevational view of a portable dock fender according to the invention, showing the fender attached to a piling in a manner reflecting its normal use in broken lines that does not form a part of the claimed design.

FIG. 2 is a front view of the portable dock fender.

FIG. 3 is a rear view of the portable dock fender.

FIG. 4 is a left side view of the portable dock fender.

FIG. 5 is a right side view of the portable dock fender.

FIG. 6 is a top view of the portable fender; and,

FIG. 7 is a bottom view of the portable dock fender.
